CLAIM

The ornamental design for a closure for bags, as shown and described.

DESCRIPTION

FIG. 1 is a perspective view of a closure for bags showing our new design.

FIG. 2 is a top plan view thereof.

FIG. 3 is a bottom plan view thereof.

FIG. 4 is a left side elevational view thereof.

FIG. 5 is a right side elevational view thereof.

FIG. 6 is a rear elevational view thereof; and,

FIG. 7 is a front elevational view thereof.

The broken lines are shown for purposes of illustrating parts of the article that form no part of the claim.

1 Claim, 5 Drawing Sheets
